UNITED STATES PATENT OFFICE.

JOSEPH F. D. HOGE, OF NEW YORK, N. Y., ASSIGNOR TO WESTERN ELECTRIC COMPANY, INCORPORATED, OF NEW YORK, N. Y., A CORPORATION OF NEW YORK.

SHAFT COUPLING.

Application filed May 11, 1922. Serial No. 560,100.

To all whom it may concern:

Be it known that I, JOSEPH F. D. HOGE, a citizen of the United States, residing at New York, in the county of New York, State 5 of New York, have invented certain new and useful Improvements in Shaft Couplings, of which the following is a full, clear, concise, and exact description.

This invention relates to an air-circulating shaft coupling.

An object of this invention is to provide a simple, efficient, inexpensive, and unitary air-circulating shaft coupling.

Fig. 1 in the drawing illustrates one embodiment of the invention as applied to a motor which drives a circuit interrupter.

Fig. 2 is a side view of the structure shown in Fig. 1.

Fig. 3 is a view on line 3—3 of Fig. 1. In Fig. 1 there is shown a motor 6 mounted on a base 3 on which there is also mounted a circuit interrupter 4 which is driven from the motor 6. The circuit interrupter 4 comprises a plurality of concentrically arranged rings, some of which are continuous, while others are segmented and over which brushes carried by a brush arm are designed to pass. The shaft upon which the distributor arm is mounted, is driven from a shaft 9 through the instrumentalities of gearing mechanism (not shown). The shaft 9 is connected with a shaft 7 of the motor 6 through a flexible coupling 8. The flexible coupling 8 consists of a pair of T-shaped members 8^b and 8^c, each of which is rigidly secured to its corresponding shaft by means of set screws 13 or other locking devices. Each of the T-shaped members 8^b and 8^c has secured in opposite ends thereof pins 12, which extend through apertures cut in a flexible member 8^a, such as rubber, leather, or the like. This member 8^a is disposed between the surfaces of the T-shaped members 8^b and 8^c to provide a connection between driving and driven shafts that will equalize small differences in angular acceleration that may occur between them and at the same time prevent binding or heating of the shaft bearings due to lack of proper alignment. The T-shaped member

8^c is disposed with respect to the T-shaped member 8^b by an angle of 90°.

In cases where excessive heating takes place due to the motor being enclosed, thus not permitting the proper ventilation, a 55 motor-cooling fan or air-circulating device 11 is arranged integral with the coupling members 8^b and 8^c. As shown in Fig. 2, the fan 11 is interposed between a surface of the coupling 8 and a surface of the flexible member 8^a. With such an arrangement, during the operation of the motor, currents of air will be forced upon the housing of the motor 6, thus serving to materially reduce the existing temperature of the motor 60 caused by its operation.

The fan structure is preferably a metal disc with a surrounding rim and with blades cut so as to project on opposite sides towards opposite edges of the rim. It is, of 70 course, obvious that other types of fan or air-circulating devices may be substituted for the specific structure disclosed without requiring the exercise of invention.

In the arrangement shown in Fig. 1, the 75 motor 6 and the circuit interrupter 4 are provided with a motor speed regulator 10, the operation of which is well known to those skilled in the art. The structure is enclosed in a casing 5. For permitting the 80 circulation of air currents through the casing 5, holes 14 are cut in each end of the casing. Currents of air are thus drawn from the openings in the casing 5 closest the circuit interrupter and caused to circulate over the casing of the motor 6 thus causing a marked degree of cooling of the motor.

The air-circulating device, which is arranged integral with the flexible coupling for connecting two shafts together, has been 90 shown as applied to a motor driving a circuit interrupter. It is, of course, obvious that other departures from the specific arrangement shown, can be made without departing from the spirit and scope of the 95 present invention.

The invention claimed is:

1. A device of the character described comprising in combination a driving member, a driven member, each comprising a 100

yoke having arms, a flexible disc, a fan having a disc-like center portion, and means projecting from the arms of said yokes for engaging said disc and said fan.

6. 2. A device of the character described comprising in combination a driving member, a driven member, each comprising a yoke, pins projecting from the ends of said

yokes, a flexible disc, a fan having a disc-like center, said disc and said fan having registered openings provided therein adapted to engage said pins.

In witness whereof, I hereunto subscribe my name this 8th day of May A. D., 1922.

JOSEPH F. D. HOGE.
